[57] **CLAIM**

The ornamental design for a hand-held electric drill, as shown and described.

DESCRIPTION

FIG. 1 is a side elevational view of the hand-held electric drill showing my new design, the electric cord being shown broken away for illustrative purposes only;

FIG. 2 is an opposite side elevational view thereof;

FIG. 3 is a rear elevational view thereof;

FIG. 4 is a reduced front elevational view thereof;

FIG. 5 is a top plan view thereof;

FIG. 6 is a bottom plan view thereof.
